FORCE-FEED LUBRICATOR

Application filed February 1, 1926. Serial No. 85,303.

The invention relates to lubricators and more particularly to devices for automatically and positively supplying oil to moving parts of machinery, such as steam and gas engine cylinders, compression and pump cylinders, bearings of every description and moving parts to minimize the friction and wear.

The invention contemplates a container for 10 the oil, a sight gage, a primary pump for delivering oil to the sight gage, so that the feed and the amount of oil supplied may be observed, and an auxiliary or dispensing pump for forcing the oil to the required 15 point of use.

While the drawings illustrate a preferred embodiment of the invention, it is to be understood that in adapting the means to meet specific needs and requirements, the design 20 may be varied and such other changes in the minor details of construction may be resorted to within the scope of the invention as claimed, without departing from the spirit thereof.

25 For a full understanding of the invention and the merits thereof, reference is to be had to the following description and the drawings hereto attached, in which,—

Figure 1 is a top plan view of a lubricator, 30 embodying the invention, the cover of the oil container being removed,

Figure 2 is a vertical sectional view on the line 2—2 of Figure 1, looking in the direction of the arrows, the cover and sight feed being 35 in place,

Figure 3 is an elevational view of the lubricator, and

Figure 4 is a detail view of the arm applied to the pump operating rock shaft.

40 Corresponding and like parts are referred to in the following description and designated in the several views of the drawings by like reference characters.

The container for the oil is designated by 45 the numeral 1 and may be of any capacity, design, and structure, and is closed at the top by a removable cover 2, which, when in position, is held in place by suitable fastening means such as stud bolts 3 welded, or otherwise made fast to the walls of the container

adjacent the upper edges thereof. The cover 2 is provided with a filling opening which is closed by means of a plug 4. A sight feed is mounted upon the cover 2 and comprises a transparent casing 5 preferably of glass, a 55 plate 6 closing the top of the casing 5 and tie rods, or bolts 7 securing the parts 5 and 6 to the cover.

A pair of oil pumps is located within the lower portion of the container and each consists of a cylinder and a plunger, the cylinders being disposed in parallel relation and connected to a wall of the container. The primary pump is designated by the numeral 8 and the auxiliary, or dispensing pump by 60 the numeral 9. The cylinder of the primary pump 8 is provided in a side with a feed opening 10. A pipe 11 projects vertically from the cylinder of the dispensing pump 9 and passes through the cover 2 and terminates within the lower portion of the casing 5 of the sight feed. A pipe 12 projects upwardly from an end of the cylinder of the primary pump 8 and its upper end passes 65 through the cover 2 and extends into the upper portion of the casing 5 and is recurved and terminates in vertical line with the pipe 11 from which it is spaced a suitable distance to admit of ready observation of the oil discharging from the upper delivery end of the 70 pipe 12 into the upper receiving end of the pipe 11. The pump 8 includes a plunger 8^a and the pump 9 embodies a plunger 9^a and these plungers operate in suitable guides 13 secured to the wall of the container opposite 75 that to which the pump cylinders are connected.

A yoke 14 connects the plungers 8^a and 9^a for simultaneous movement and this yoke terminates in pintles 15 which enter slots 16 80 in the free ends of arms 17 attached to a rock shaft 18 mounted in opposite sides of the container 1 and having an end extended and provided with an arm 19 which may be connected in any convenient and determinate way with 85 a moving part for operating the device. The operating arm 19 is provided in its length with a plurality of openings 20, whereby the operating part may be adjustably connected thereto.

In practice, the container 1 is supplied with oil and the auxiliary, or dispensing pump 9 is connected by means of a pipe 21 with the part, or parts to be lubricated. The rock shaft 18 is oscillated and through the connections shown and described imparts a reciprocatory movement to the pump plungers 8^a and 9^a. Upon the out-stroke of the plungers, the opening 10 and the lower end of the pipe 11 are uncovered and oil passes from the container 1 to the cylinder of the pump 8 through the feed opening 10 and any oil that may have been supplied to the pipe 11 passes therefrom into the cylinder of the dispensing pump 9. Upon the forward stroke of the plungers 8^a and 9^a oil is discharged from the pump 8 and pipe 12 into the pipe 11 and from the pump 9 into the distributing pipe 21, it being assumed that the pipe 12 and cylinder of the pump 8 have been previously charged. The oil forced from the cylinder of the dispensing pump 9 is conveyed to the parts to be lubricated by means of the pipe 21, as will be readily understood. It is observed that branches, not shown, are adapted to be connected to the distributing pipe 21 to convey the oil therefrom to the parts to be lubricated.

Having thus described the invention, I claim:

- 30 1. A force feed lubricator comprising a container, primary and auxiliary pumps disposed horizontally in said container and each including a cylinder carried by a wall of the container, the auxiliary pump having an outlet externally of the container and a vertically disposed inlet pipe within the container and open at its upper end, said primary pump having an inlet within the container and an outlet pipe extending upwardly from its cylinder and terminating in a curved upper end portion disposed over the open upper end of the inlet pipe of said auxiliary pump, plungers for the cylinders of said pumps slideable into and out of the cylinders through open ends thereof, a yoke extending transversely between and secured to said plungers and having its end portions extending therefrom and reduced to form pintles, a rock shaft rotatably carried by walls of the container and extending above said plungers in crossed relation thereto with one end projecting outwardly from the container, depending arms adjustably carried by said shaft and extending radially therefrom and having their lower free end portions formed with longitudinally extending slots slidably receiving the pintles of said yoke, and an actuating handle carried by the outer end portion of said shaft.
- 60 2. A force feed lubricator comprising a container, pumps disposed horizontally in said container and each including a cylinder carried by a wall of the container and open at its inner end, plungers for the cylinders of said pumps slideable into and out of the cylinders through the open inner ends thereof, a

yoke extending transversely between and secured to said plungers and having its end portions provided with pintles, a rock shaft rotatably carried by walls of the container and extending above said plungers in crossed relation thereto with one end projecting outwardly from the container, depending arms adjustably carried by said shaft and extending radially therefrom and having slotted lower free end portions straddling the pintles of said yoke, and an actuating handle carried by the outer end portion of said shaft.

In testimony whereof I affix my signature.

WILLIAM H. STAINBROOK. [L. S.]
